(57) **CLAIM**

The ornamental design for an portion of a display screen with animated graphical user interface, as shown and described.

DESCRIPTION

FIG. 1 is a front view of a first image of a first embodiment of a portion of a display screen with animated graphical user interface showing our new design;

FIG. 2 is a front view of a second image thereof;

FIG. 3 is a front view of a third image thereof;

FIG. 4 is a front view of a fourth image thereof;

FIG. 5 is a front view of a first image of a second embodiment of a portion of a display screen with animated graphical user interface showing our new design;

FIG. 6 is a front view of a second image thereof;

FIG. 7 is a front view of a third image thereof; and,

FIG. 8 is a front view of a fourth image thereof.

In the first embodiment, the appearance of the transitional image sequentially transitions between the images shown in FIGS. 1 through 4. In the second embodiment, the appearance of the transitional image sequentially transitions between the images shown in FIGS. 5 through 8. The process or period in which one image transitions to another image forms no part of the claimed design.

The outer broken line rectangle showing of a mobile device and features of a mobile device are included for the purpose of illustrating environmental structure, the inner broken line rectangle showing of a display screen and all other broken lines showing portions of the graphical user interface are included for the purpose of illustrating portions of the article; broken lines form no part of the claimed design.
